UNITED STATES PATENT OFFICE

WAYNE S. SEARLES, OF PROVIDENCE, RHODE ISLAND, ASSIGNOR TO UNIVERSAL OPTICAL CORPORATION, A CORPORATION OF RHODE ISLAND

DESIGN FOR BAR MATERIAL FOR OPHTHALMIC MOUNTINGS

Application filed November 14, 1931. Serial No. 41,733. Term of patent 14 years.

To all whom it may concern:

Be it known that I, WAYNE S. SEARLES, a citizen of the United States of America, residing in Providence, county of Providence, State of Rhode Island, have invented a new, original, and ornamental Design for Bar Material for Ophthalmic Mountings, of which the following is a specification, reference being had to the accompanying drawings, forming a part thereof.

Fig. 1 is a top plan view of a portion of a length of bar material for ophthalmic mountings showing my new design; and Fig. 2 is a sectional view of the same on line 2—2 of Fig. 1.

I claim:

The ornamental design for bar material for ophthalmic mountings, substantially as shown.

WAYNE S. SEARLES
